UNITED STATES PATENT OFFICE.

PETER HEALEY, OF EVANSVILLE, INDIANA.

STOP AND WASTE COCK.

SPECIFICATION forming part of Letters Patent No. 770,178, dated September 13, 1904.

Application filed January 9, 1904. Serial No. 188,415. (No model.)

To all whom it may concern:

Be it known that I, PETER HEALEY, a citizen of the United States, residing in Evansville, in the county of Vanderburg and State 5 of Indiana, have invented certain new and useful Improvements in Stop and Waste Cocks, of which the following is a full, clear, and exact description, reference being had to the accompanying drawings, forming part of this 10 specification.

My invention relates to a stop and waste cock so constructed as to be operated by either right or left hand movement of the plug-valve in the cock, thereby avoiding the necessity of 15 making separate cocks for right and left hand use.

The invention consists in features of novelty hereinafter fully described, and pointed out in the claim.

20 Figure I is a plan view of my stop and waste cock with the handle thereof omitted. Fig. II is an elevation of the cock with the handle shown in place therein. Fig. III is a face view of the neck of the cock and the head of 25 the plug-valve seated in said neck. Fig. IV is a cross-section taken on line IV IV, Fig. II. Fig. V is a cross-section of the cap by which movement of the plug-valve is governed. Fig. VI is an enlarged perspective view of the neck 30 of the cock and head of the plug-valve passing therethrough, the plug-valve-controlling cap being shown in cross-section.

1 designates the housing of my stop and waste cock, which is designed to have its ends 35 united to sections of pipe leading thereto, as seen in Figs. I and II. Projecting from the front of the housing 1 is the usual drain-nipple 2. Mounted in the housing 1 is a plug-valve having in its body the ports common to drain-cock plug-valves.

3 designates the neck of the cock-housing 1, from which extend a pair of bosses 4, located diametrically opposite each other.

5 designates the head of the plug-valve, 45 which projects through the neck 3 and the main body of which extends beyond the bosses 4, terminating in a shoulder-seat 6.

7 is the outer circular end of the plug-valve head that extends beyond the shoulder-seat 6

and contains a socket 8, by which a handle 9 50 is received.

10 designates a cap having an inwardly-extending rim 11, that rests upon the shoulder-seat 6 of the plug-valve head and within which is an aperture 12, that receives the outer end 55 7 of the valve-head. The cap 10 also has a flange 13, that extends inwardly from the rim 11 and is fitted to the bosses 4, carried by the cock-housing neck, as seen in Figs. II, IV, and VI. On the interior of the flange 13 is a 60 single boss 14.

15 is a set-screw that passes through the cap-flange 13 and boss 14 interior thereof, as seen most clearly in Figs. IV and V. This set-screw is adapted for insertion through a 65 screw-threaded hole 5^a, extending through the main body of the plug-valve head 5 to the socket 8, that receives the handle 9.

When the cap 10 is applied to the head of the plug-valve of my stop and waste cock, its 70 rim 11 rests upon the shoulder-seat 6 of the plug-valve head-body, as seen most clearly in Fig. VI, and the outer end of the cap is thereby held away from the bosses 4 of the cock-neck, so as to ride entirely with the head of 75 the plug-valve without any bearing against the ends of the bosses 4. After the cap has been seated, as stated, the set-screw 15 is inserted through the flange 13 and boss 14 of the cap is introduced through the hole 5^a in 80 the plug-valve head and the cap is thereby firmly united to the plug-valve with the boss 14 of the cap occupying a position between the neck-carried bosses 4, thereby limiting the movement of the plug-valve to a degree permitted by the space existing between opposing faces of the bosses 4. The movement for 85 the plug-valve thereby provided is rendered either right or left hand according to the position of the cap-boss 14. Where it is desired 90 to provide opposite movement of the plug-valve, the cap 10 is removed from the valve and turned to position its boss 14 between opposing faces of the bosses 4 opposite that in which it was previously located, and the 95 valve is rotated to bring the hole 5^a in the valve to the side occupied by the cap-boss, and by then inserting the set-screw into the

hole 5^a the desired reverse movement of the plug-valve is secured. The set-screw 15, by extending through the plug-valve head into the socket 8 therein, serves to hold the handle 9 in place in said socket by engaging the inner end of the handle, as seen in Fig. IV.

I claim as my invention—

In a stop and waste cock, the combination of a housing-neck, a pair of bosses projecting from said neck, a plug-valve having a head provided with a threaded hole, a shoulder-seat on said valve-head located beyond the ends of said neck-carried bosses, a circular end projecting from said valve-head beyond said shoulder-seat, a cap having a central orifice fitted to said circular valve-head end, a rim

forming a part of said cap resting on said shoulder-seat and thus keeping the cap from frictional engagement with the end face of said neck-carried bosses, a straight flange extending from said rim to a point below the lower terminus of said neck-carried bosses, a boss on the interior of said flange intermediate of said neck-carried bosses, said flange and boss having a threaded hole registering with the threaded hole in the plug-head, and a set-screw passing through said threaded holes, substantially as set forth.

PETER HEALEY.

In presence of—

ANDREW J. CLARK,
R. J. VIETS.
